Primary Examiner — Catherine A Tuttle*(74) Attorney, Agent, or Firm* — True Shepherd LLC;
Andrew C. Cheng(57) **CLAIM**

The ornamental design for a rotating magic bean toy, as shown and described.

DESCRIPTION

FIG. 1 is a top front perspective view of a rotating magic bean toy showing my new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the rotating magic bean toy that form no part of the claimed design.

1 Claim, 8 Drawing Sheets(56)
